CATALYTIC CRACKING PROCESS

Luis de Florez, Pomfret, Conn.

Application March 25, 1939, Serial No. 264,064

2 Claims. (Cl. 196—52)

This invention relates to a method for the production of motor fuel from petroleum and more particularly relates to the application of heat and catalytic material to the petroleum for this purpose.

This is a continuation in part of a pending application Serial No. 208,732, filed May 19, 1938, by the same applicant now United States Patent 2,237,339, issued April 8, 1941.

For a further description of this invention reference may be had to the drawing which shows in somewhat diagrammatic form an apparatus for carrying out the process.

The fresh charge enters the system at point 10 at the top of the fractionating tower 12, passing over the trays 14 and accumulating in the pan 16. In its passage through this part of the system the charge is heated and absorbs and condenses part of the vapors rising through the column 12. From the pan 16 the heated charge remaining liquid, together with such condensates as have been formed by contact with the charge in passing over the trays, passes out through line 18 having the valve 20, into the stripping column 22. In this vessel the heavy liquid portions of the charge fall to the bottom and are picked up by pump 24 and discharged through line 26 into the top of the coking chamber 28. The overhead from the stripper 22 passes out through a cooling coil 30 into a receiver 32 where the liquid portions are picked up by pump 34 and discharged through line 36 into another fractionator 38. The stripper 22 and the receiver 32 may be operated under a vacuum imposed by pump 40.

The overhead from column 12 passing out through line 42 passes into the base of the fractionator 38. The vapors rise through this vessel which is equipped with suitable trays, not shown, and pass out through line 44 and condenser 46, into a receiver 48 where liquid motor fuel separates out at the bottom and fixed gases, if any, are discharged from the top. A portion of the overhead from fractionator 12 is condensed in fractionator 38 as a result of cold oil introduced into fractionator 38 through the line 50. This cooling oil may be brought in from any suitable part of the system.

The material accumulating in the base of fractionator 38 composed of the liquid portions of the overhead discharged from pumps 34 and 52 is picked up by main circulating pump 54 and discharged through line 56 into the heating coil 58 of the heater 60. This material is then heated in the coil 58 and discharged through the line 61 having valve 62 into the reaction chamber 28.

The hot vapors or oil entering the chamber 28 pass upwardly and meet the steam of heavy materials discharged by pump 24 through the line 26. An exchange of heat occurs, raising the temperature of the mixture to such a point that the material is eventually distilled leaving solid "residue" in the chamber 28. The overhead from the chamber 28 passes through the line 64 into the fractionator 12 where liquid and vapors are separated, the vapors passing overhead to come in contact with the entering charge. The liquid portions accumulate in the base of the fractionator 12 and are passed out into a stripper 66. The liquid portions in the bottom of the vessel 66 are drawn off in line 68 and constitute a discharged intermediate product. The overhead from the stripper 66 is cooled in cooler 70 and discharged by means of pump 52 into fractionator 38 completing the cycle at this point.

A slurry containing a solid catalytic material which has been prepared in the mixing system 72 is picked up by pump 74 and passed through line 76 to any one of a plurality of discharge points 18, 80, 82 or 84. The branches of the pipe 76 contain suitable valves, of course, so that the catalyst can be injected into the system at the desired point. In order to permit the handling of the solid catalytic material, it is mixed with a suitable liquid such as water or a light hydrocarbon admitted to the mixer at 85 and in a sufficiently liquid state to be handled by a suitable pump such as 74. The material is agitated by any suitable means such as the pump 86 and its connections.

It is believed that the operation will be clear from the foregoing description. However, to summarize, it will be seen that the charge material is first heated and separated into light and heavy constituents in the fractionator 12, the lighter constituents entering into the circulation through the heating coil 58 and the heavy constituents being injected into the reaction coking zone directly. In the passage through the heater the lighter portions of the charge together with those portions of the material which have not been sufficiently converted are passed through the coil and brought at a reaction temperature into contact with the catalytic material which may be injected at any of a number of points in the reacting zone or zones. The catalytic material which has been brought into the system in a liquid or semi-liquid form is subjected to a relatively high heat and the liquid which carries the catalytic material is vaporized or otherwise separated from the catalytic material allowing this

latter to become free in contact with the material under treatment. After conversion occurs, lighter or more volatile hydrocarbons are formed and likewise polymerization products are formed. The polymerization products tend to remain in contact with the catalytic material and in turn the catalytic material will tend to be enveloped by tarry particles which will separate themselves out in the reaction chamber and gradually be reduced to a solid coke-like material to deposit in the coke chamber 28 from which they are removed by a suitable coke drilling or removing mechanism indicated in the drawing as 88.

Thus it will be seen that the catalytic material is injected into the system, contacted with the material under treatment and removed from the system in a continuous manner. While only one coke chamber 28 has been shown, in order to make the operation continuous, a plurality of such chambers will preferably be used with suitable connections so that one chamber may be shut off to be cleaned while another is connected in the system in a manner similar to that disclosed in the aforementioned pending application Serial No. 208,732.

This operation may be carried out under varying pressures and temperatures depending upon the material to be treated and the type of catalyst employed. The injection of the catalyst may be made at different points to vary the time in which it is in contact with the material under treatment. As an example of the operation of the invention, a charging stock such as crude oil, reduced crude, gas oil, or heavy naphtha, is contacted in the upper section of a primary dephlegmating tower with cracked vapors from the system, whereby the lighter constituents of the charge are vaporized and the heavier components of the cracked vapors condensed. The condensed liquid is withdrawn through line 18 to a vacuum stripper 22 for further reducing to a heavy liquid which is withdrawn from the bottom of the stripper and pumped through line 28 to the top of the reaction chamber 28. The vapors from the stripper 22 pass overhead and condense in 30, after which they are collected in 32 and passed to the fractionating tower 38 where they are blended with the liquid condensate and pumped through line 58 to the heater 68 which is maintained under a pressure of from 100 to 200 pounds. In the heater the temperature of the recycle stock is raised to about 1000° before mixing with the catalyst slurry which may be admitted, as has been pointed out hereinbefore, at any one of several points. The hot products in the vapor phase are then transferred to the reaction drum 28 where they are intimately contacted with the catalyst. After contacting with vapors, the clay settles out in the lower portion of the reaction drum while the vapors pass overhead to the primary dephlegmating zone, mentioned heretofore. The clay settling out in the lower portion of the reaction drum with coke formed therein is intermittently removed by cutting out one reaction drum and passing the

cracked products to another reaction drum previously cleaned. The bottom section of the primary dephlegmating tower 12 may be suitably cooled to produce a heavy liquid condensate which is withdrawn from the bottom to a stripper 68 where it is flashed into an overhead vapor. The vapor is condensed and cooled in 70 and pumped back into the fractionating tower 38 for further treatment. An intermediate oil liquid such as 10 fuel oil is withdrawn from the bottom of the stripper through line 68.

The process which has been described permits the withdrawal of an intermediate liquid product which is not returned to the coking zone, thus 15 decreasing the quantity of coke made per barrel of charge. This intermediate liquid product represents a highly degraded material which if returned to the coking zone would deposit a very large proportion of coke and would produce a relatively large proportion of gas. The conversion of such a material is far less favorable than the conversion of the material selected for re-treatment. This degraded material is more useful in the form of an intermediate distillate suitable for fuel oil than as a material to re-treat.

Obviously, many modifications and variations of the invention as above set forth may be made without departing from the spirit and scope thereof, and therefore only such limitations should be imposed as are indicated by the appended claims.

I claim:

1. A process for the conversion of hydrocarbon oil which comprises heating the oil to conversion temperatures in a heating zone, mixing a slurry of a catalyst and a carrier liquid with the heated oil, subjecting the mixture of oil and catalyst to reaction in an enlarged conversion zone, withdrawing vapors from the conversion zone, separating from these vapors a heavy liquid which is withdrawn from the system, contacting fresh charge with the uncondensed vapors in a fractionating zone thereby condensing a portion of the vapors and vaporizing a portion of the charge, passing a mixture of unvaporized charge 35 and reflux condensate from said fractionating zone to a stripping zone maintained under vacuum and there stripping said mixture to form vapors and a residuum, condensing said vapors, recycling said residuum to said conversion zone, 40 passing a mixture of fresh charge vapors and conversion zone vapors from the fractionating zone to a second fractionating zone, passing the condensate formed from the vapors from the stripping zone to said second fractionating zone, 45 fractionating the vapors and condensate in said second fractionating zone to form gasoline and a clean recycle stock, and returning said clean recycle stock to said heating zone.

2. The process of claim 1, in which the heavy 50 liquid which is withdrawn from the system is first flashed into an overhead vapor and said vapor condensed and passed to the second fractionating zone.
